GLOVE

Julius A. Higier, Johnstown, N. Y.

Application October 7, 1953, Serial No. 27,099

Term of patent 7 years

(Cl. D3—11)

To all whom it may concern:

Be it known that I, Julius A. Higier, a citizen of the United States of America, residing in Johnstown, county of Fulton, and State of New York, have invented a new, original, and ornamental Design for a Glove, of which the following is a specification, reference being had to the accompanying drawing, forming part thereof, wherein,

Figure 1 is a rear view of a glove showing my new design with the index and middle finger members spread apart to bring out the details of the superimposed tabs.

Figure 2 is a front view thereof, drawn to a smaller scale, showing the thumb member in pulled back position.

The drawing is shaded to indicate leather on the finger tabs, palm section and the ornamentation on the back of the glove.

I claim:

The ornamental design for a glove, substantially as shown and described.

JULIUS A. HIGIER.
